Primary Examiner — Sandra Snapp*Assistant Examiner* — Ieisha Price(74) *Attorney, Agent, or Firm* — Andrus Intellectual Property Law, LLP**CLAIM**

The ornamental designs for a vehicular flag pole, as shown and described.

DESCRIPTION

FIG. 1 is a front view of an embodiment of a vehicular flag pole;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines in the drawings illustrate portions of the vehicular flag pole and form no part of the claimed design. The dash-dot-dash broken line illustrates the bounds of the claim.

1 Claim, 4 Drawing Sheets(56)
